UNITED STATES PATENT OFFICE.

HENRY W. JACOBS, OF SHREVEPORT, LOUISIANA.

TOBACCO-PIPE.

1,013,019.

Specification of Letters Patent. Patented Dec. 26, 1911.

Application filed March 21, 1911. Serial No. 615,827.

To all whom it may concern:

Be it known that I, HENRY W. JACOBS, a citizen of the United States, residing at Shreveport, in the parish of Caddo and State of Louisiana, have invented new and useful Improvements in Tobacco-Pipes, of which the following is a specification.

This invention relates to tobacco pipes and the object of the invention is the provision of means for cooling the smoke in its passage from the bowl to the mouthpiece and for collecting moisture.

A further object of the invention is the provision of means for cooling the smoke from the bowl to the mouthpiece and means for holding a cooling element within the stummel.

A still further object of the invention is the provision of a pipe having a removable smoke cooling tube mounted therein and means for maintaining said tube cool throughout its length.

Further objects of the invention will appear as the following specific description is read in connection with the accompanying drawing, which forms a part of this application, and in which:—

Figure 1 is a perspective view. Fig. 2 is a longitudinal sectional view. Fig. 3 is a detail perspective view of the cooling tube removed. Fig. 4 is a section on the line 4—4 of Fig. 2.

Referring more particularly to the drawing, 1 represents the bowl which is hollowed out, as is usual, at 2 to receive the tobacco and is provided with a central channel 3 in its bottom which communicates with a passage 4 extending through the stummel 5, which is provided with a plurality of apertures 6 through its length. The passage 4 forms a chamber of relatively large diameter and is closed at its ends by apertured disks 7 and 8 which are threaded or otherwise secured in the ends of the stummel. A suitable mouthpiece 9 is secured in the disk 8 and the lower end of the stummel is curved downwardly, as shown at 10, with the disk 7 therein closed by a plug 11.

Extending from the disk 7 to the disk 8 and connected to both in any suitable manner is a tube 12 made of any suitable material and provided with a lateral tubular extension 13 adapted to communicate with the channel 3 in the bottom of the bowl. This tube is covered throughout its length

by a suitable absorbent fabric 14. Forming a part of the bowl is a cup 15 which is closed at its top by a plug 16 and is provided with a channel 17 leading to the chamber 4. This channel has a tube 18 mounted therein which projects above the bottom of the cup and carries an absorbent packing 19 which permits the liquid 20 therein to gradually be absorbed by the fabric 14 on the tube 12, the packing 19 being 65 in contact with said fabric.

Any suitable cooling liquid may be used which will not effect the aroma of the tobacco and as air is continually circulating around the fabric in the tube the smoke in the tube is kept in a cool state and is drawn into the mouth without the biting sensation common in most smoking pipes. The end of the tube 12 forms a saliva chamber which may be emptied by removing the plug 11. 70 Any moisture in the smoke will be condensed upon the chilled inner surface of the tube and will flow downwardly to the end thereof, together with the coarser impurities which are collected by the moisture. 75

Having thus described the invention, what I claim as new is:—

1. A pipe comprising a bowl, an apertured stummel secured thereto having an enlarged channel, a mouthpiece secured to 85 the stummel, a smoke tube passing through the stummel free of the walls thereof and connected to the bowl and mouthpiece, and a foraminous wrapping on the smoke tube.

2. A pipe comprising a bowl, a stummel secured thereto having an enlarged channel, a smoke tube mounted in the channel free of the walls thereof, a mouthpiece connected to the tube, means for connecting the smoke tube to the bowl, means for closing the end 95 of the smoke tube opposite from the mouthpiece, and a fabric wrapping for the tube.

3. A pipe comprising a bowl, a stummel secured thereto, a smoke tube mounted in the stummel and free of the walls thereof, a mouthpiece connected to the tube, a foraminous wrapping for the tube, and means to keep said wrapping moistened.

4. A pipe comprising a bowl, an apertured stummel secured thereto and having 105 an enlarged channel, a smoke tube mounted in the channel free of the walls thereof, a fabric wrapping for said tube, a mouthpiece communicating with the tube, a communicating connection between the tube and the 110

bowl, a liquid reservoir, and means to gradually convey moisture therefrom to the fabric around the tube.

5. A pipe comprising a bowl having a
stummel secured thereto, a smoke tube
mounted in the stummel and separated
therefrom, a fabric wrapping for said tube,
a liquid receptacle connected to the bowl, a
tube passing through said receptacle into
10 the stummel, an absorbent material car-

ried in the tube and engaging the fabric
around the smoke tube, and a mouthpiece
connected to the smoke tube.

In testimony whereof I affix my signature
in presence of two witnesses.

HENRY W. JACOBS.
